BAG FRAME

William C. Hiering, Millburn, N. J., assignor to
 J. E. Mergott Company, Newark, N. J., a corporation of Delaware

Application September 23, 1932, Serial No. 634,496

3 Claims. (Cl. 150—29)

This invention has reference to improvements in the manufacture of frame-sections for bags and purses, especially for travelling chatelaine and similar bags.

5 The object of my invention is to provide a novel means for positively connecting the bent or right-angled portions of the members of the frame-section at a point where the pivot members are bent with the main body at right angles, without 10 out the use of rivets or solder, and without causing the metal to pucker, crack or break at the said corners and producing neat and sharp-cornered angle members.

The principal object of the invention is to provide 15 a simply constructed bag frame-section which consists of a main body and a right-angled pivot member at each end of said main body, the said main body and said right-angled pivot member having secured thereto an angle-plate, 20 and which is secured to the corner of the frame by means which are integral with the main body and the pivot member, said means being forced inwardly over and into intimate contact with the angle-plate which is fitted over the junction of said main body and pivot members, and which is secured in position by said integral means.

The invention is clearly illustrated in the accompanying drawing, in which:

Fig. 1 represents a perspective view of a frame 30 section embodying the principles of my present invention,

Fig. 2 represents a fragmentary perspective view of a portion of the blank from which the frame is made, showing by the curved arrow, the 35 manner in which the right angle pivot members are formed, after which the angle-plate is positioned at the junction of the main body and pivot member, as indicated by the straight arrow,

Fig. 3 represents a side elevational view of a 40 corner portion of the frame member embodying the principles of my invention, and

Fig. 4 represents a view taken on lines 4—4 of Fig. 3 in the direction indicated by the arrows.

Similar characters of reference are employed 45 in the above-described views to indicate corresponding parts.

In the drawing, reference character 1 represents a complete frame section embodying the principles of my present invention, the same 50 comprising a main body portion 2 and the end or pivot members 3, made from a suitable blank, shown fragmentarily in Fig. 2 in the manner indicated by the curved arrow and dotted lines in said figure.

55 Reference character 4 represents an angle-

plate adapted to be fitted over the junction of the main body 2 and the pivot member 3. The angle-plate is rigidly held against displacement by the inwardly extending projections 5—5 which are formed upon the main body and pivot members and overlap the angle-plate 4, whereby all the parts will be tightly bound together and separation of the pivot members from the main body 2 due to any undue strain that may be produced upon the corners of the completed 10 frame will be prevented.

While I have shown my invention applied to outwardly channelled bag frame sections, it will be obvious that my invention may be equally well applied to upwardly, inwardly or downwardly 15 channelled frame sections and that it may be equally well applied to bag frame sections having unitary or mitered corners. The frame member shown in Fig. 1 of the drawing is of the channel type, the walls of the channel opening out laterally from the pouch.

The inwardly extending projections 5 are shown as applied to the inner walls of the channelled frame section at the corners thereof, but the same may be applied to the outer wall with 25 equal efficacy and one, two or more projections 5 may be provided at each corner of the frame section as desired.

It will be thus seen that I have produced a simple means of connecting the pivot members 30 to the main body section for providing the bag frame section with sharp angled corners to produce a neat and strong frame without the use of solder, rivets or other extraneous means and that the corners of the frame section are effectively reenforced and protected from distortion 35 by my invention.

The foregoing disclosure is to be regarded as descriptive and illustrative only, and not as restrictive or limitative of the invention, of which 40 obviously an embodiment may be constructed including many modifications without departing from the general scope herein indicated and denoted in the appended claims.

Having thus described my invention, what I 45 claim as new and desire to secure by Letters Patent, is:

1. A bag frame section formed from a single, channelled, blank of material provided with a cut-away portion, the channel of the frame opening 50 out laterally from the pouch, said blank being bent at right angles to close the cut-away portion and to provide a mitered, smooth, right-angled corner, and means to reinforce the mitered corner of the frame section and prevent 55

the distortion of the same, said means comprising an angle plate fitted over the mitered corner of the frame and inwardly extending projections formed upon the inner wall of the channelled frame section between the points at which the edges of the inner wall of the frame meet and the outer ends of the angle plate, said inwardly extending projections being forced inwardly over and into intimate contact with said angle plate and for securing said plate in position.

2. A bag frame comprising a channelled bag frame member having a main body and an integral pivot member at each end of said main body, said frame having mitered, sharp angle corners, angle plates positioned within the channel of the frame member over the mitered corners thereof, said angle plates extending well into the channels of the frame to provide ample reinforcement for the mitered corners, and inward-

ly extending projections formed on a wall of the channelled frame, said inwardly extending projections being spaced from and adjacent the mitered corners of the frame and extending over and in intimate contact with said angle plates for securing said angle plates in position. 5

3. A bag frame comprising a channelled bag frame member having a main body and an integral pivot member at each end of said main body, said frame having mitered, sharp angle corners, angle plates positioned within the channel of the frame member extending well over the mitered corners thereof, and inwardly extending projections formed on a wall of the channelled frame at a distance from the mitered corners, 10 15 said projections extending over and in intimate contact with said angle plates for securing said angle plates in position.

WILLIAM C. HIERING.
